SAFETY RAZOR

Harry R. Hodge, New York, N. Y.

Application April 29, 1940, Serial No. 332,163.

3 Claims.

This invention relates to safety razors, and more particularly to that type of safety razor wherein the blade is manually reciprocated. The razor of the invention has particular utility for quick and emergency use because of its manual features, its compactness and small number of parts.

It is common practice in the field of razor manufacture to utilize motor driven blades in safety razors for shaving. It is also common practice in this field to manufacture safety razors in which the blade is movable by manually operated gearing, in which the operating means consists of grooved or roughened rollers adapted to engage the skin and bring about reciprocation of the movable blade. As a rule razors of both types mentioned tend to be somewhat complicated in their structure and somewhat large and cumbersome.

It is one of the important objects of the present invention to provide a safety razor which by reason of its relatively small size may be readily carried about the person. Another object of the invention is to provide a safety razor having a simplified construction enabling the unit to be manufactured and retailed for a relatively low price. A further object is to provide a safety razor combining simplicity of design with a pronounced degree of efficiency in the cutting operation. Various other objects will appear on consideration of the following description of an embodiment of the invention which may be preferred, and of the accompanying drawing illustrating said embodiment, in which:

Fig. 1 is a plan view of the razor;

Fig. 2 is a sectional view taken along lines 2-2 of Fig. 1, showing the mode of application of the razor to the face;

Fig. 3 is a side view of the cutting portion of the razor:

Fig. 4 is a plan view of the razor head; and
Fig. 5 is a detail showing the cutting teeth of
the razor blades.

As shown in Fig. 1, the razor 10 is provided with a handle 11 of any convenient type and material, which is attached to the razor unit 12. This razor unit consists of a rectangular frame 13 of strip metal, the ends of which form a junction on the handle side of the razor. Adapted to be inserted and supported within this frame are three members, the roller 14, the movable razor blade 15 and the stationary razor blade 16. The roller 14 consists of a central pin 17 of metal, the ends of which are adapted to protrude through the circular openings 18 formed in

(Cl. 36—43)

opposite ends of the frame 13. Fixed to the pin 17 is the core 19 of the roller, about which, at opposite ends, a layer of surfacing material, such as rubber or plastic composition, is formed to obtain two skin bearing surfaces 20 and 21. In order to improve the face gripping characteristic of this surfacing material, the surface of the same is ridged as at 22, or otherwise roughened or modified to secure a non-slip grip on the skin. Between the two skin bearing surfaces 20 and 21 of the roller, and of lesser diameter relative thereto, is a central ring 23 of metal or other suitable material, around the periphery of which a zigzag cam groove 24, having radial walls 25 and a base 26 concentric to the roller pin 17, is formed. The purpose of this cam groove 24 is to afford means for bringing about rectilinear oscillation of the movable blade, as will be described hereinafter. Intermediate the roller 14 and the outer transversely curved end section 27 of the frame 13 are positioned the stationary and movable razor blades 15 and 16. The stationary blade 16 is in the shape of an elongated bar or plate 28 suitably attached to the frame section 27 and having at the side edges projecting teeth 29, which extend outwardly and are curved to the inside, these teeth tapering into a sharp point 30 and forming a thin rigid grid, as shown in Figs. 1 and 5. Hardened steel is employed in these projecting teeth of the stationary razor blade so as to insure maintenance of the normal curvature of the same with adequate resistance against deformation while the razor is employed in the shaving operation. The tendency of the stationary razor blade teeth to deform is also resisted by the adjacently positioned movable razor blade 15. This blade consists of an elongated bar or strip 31 interposed between the roller 14 and the stationary blade 16, having attached separably or integrally to the side edges a plurality of outwardly extending cutting teeth 32. As shown in Figs. 1 and 2, these teeth are of substantial radial thickness and of a width approximately the same as that of the stationary teeth. The ends of the teeth 32 extend beyond the ends of the teeth 29, as shown in Fig. 5, thereby constituting, either in the state of rest or motion, a substantial support to the stationary teeth 29. The movable blade is attached to the frame 13 by means of pins 33 which may be round or of other conformation and which extend from the ends of the plate 31 of the movable blade 15 through opposite apertures 34 in the frame to a point beyond the same, so that the blade may be re-

ciprocated without radial displacement from its position. Rectilinear motion is imparted to this blade by means of a pin 35 attached to the movable blade bar 31 at its mid-point and extending into the groove 24, the sides of the pin engaging the walls 25 of said groove.

The operation of the razor may now be described. The unit is applied to the skin, indicated at 40 in Fig. 2, with the roller 14 and rounded teeth 29 of the stationary blade engaging the skin. The razor is then reciprocated manually. As the roller 14 is moved through engagement with the skin surface, the zigzag cam groove 24 causes a rectilinear movement of the pin 35 which, since it is a part of the movable blade, causes the blade to move back and forth rectilinearly, thus bringing about a shearing or cutting action with the stationary blade teeth. Since the cutting surface of both the stationary and movable blades are formed as teeth with end openings, the downward movement of the razor permits the hair on the skin surface readily to enter into engagement with the cutting surface, the combing action tending to lift up the hair and insure such engagement. Also, since the cutting teeth are curved, as shown in Fig. 5, when the razor is moved in such direction that the blade teeth are following instead of leading on the skin surface, this curvature permits entrance of the hair ends between the teeth also, so that cutting operation is possible in whichever direction the razor is reciprocated by the hand, that is, either moving up or moving down over the skin surface.

In this connection it is pointed out that the skin surface is maintained taut, whichever way the razor is moved. When moved downwardly in the direction of the full arrow the roller tends to pull the skin taut under the cutting blades. When moved upwardly the outer surface of the stationary blade engages the skin surface to remove all slack.

Attention is directed to the simplicity of the razor in that it is formed of only five separable parts: the handle 11, the razor frame 13, the roller 14, the movable blade 15 and the stationary blade 16. Attention is also directed to the fact that the roller is interposed in line with the handle and frame top 27, and since its diameter is greater than that of the razor blades its bearing surface projects outwardly on both sides of the razor head. Consequently, reciprocation of the movable blade may be accomplished on either side of the razor, and to utilize this function of the unit stationary and movable teeth of duplicate structure are formed on both sides of the base plates 28 and 31 of the razor blades.

Modifications of the invention may, of course, be made and hence I do not desire to be limited to the details of the specific disclosure except insofar as limitation is required by the scope 5 of the claims hereto appended.

I claim as my invention:

1. A safety razor comprising a flat frame forming a supporting structure and provided with a straight section, a stationary blade fastened to 10 said frame section and having edges extending beyond the frame structure on both sides thereof, a movable blade and a roller each mounted on said frame, the movable blade being positioned between the roller and stationary blade and in 15 operative contact with said stationary blade, and means for transferring movement from the roller to the movable blade, said means including a zig-zag cam slot medially positioned on the periphery of the roller, and a cam member fixed to the movable blade adjacent the midpoint and 20 on the roller side thereof, said member being adapted to move in said roller cam slot and said roller and blades extending beyond said frame on both sides thereof.
2. A safety razor comprising a flat open frame forming a continuous closed structure and provided with a straight section, a stationary blade fastened to said frame section and having edges extending beyond the frame structure on both 25 sides thereof, a movable blade and a roller each mounted on said frame, the movable blade being positioned between the roller and stationary blade and in operative contact with said stationary blade, and means including relatively slidable 30 members for transferring movement from the roller to the movable blade, said roller extending beyond said frame and blades on both sides thereof.
3. A safety razor comprising a flat frame forming a supporting structure and provided with a straight section, a stationary blade fastened to said frame section and having edges extending beyond the frame structure on both sides thereof, a movable blade and a roller each mounted on 35 said frame, the movable blade being positioned between the roller and stationary blade and in operative contact with said stationary blade, and said roller comprising a core, a layer of friction material on the end sections of said core, a central ring spacing said friction layers from each other, said ring being provided with a zig-zag cam groove on the periphery thereof, and a member projecting from and attached to the roller side of the movable razor blade and engaging 40 said roller groove, said roller and blades extending beyond said frame on both sides thereof.

HARRY R. HODGE.
